CASTING MACHINE

Nathan Lester, Shaker Heights, and Thomas J. Lester, University Heights, Ohio, assignors to Lester Engineering Company, Cleveland, Ohio, a corporation of Ohio

Application August 6, 1946, Serial No. 688,612

15 Claims. (Cl. 18—16)

1

The present invention relates generally to improvements in a casting machine for producing, for example, castings from thermoplastic materials and more particularly to improvements in the mechanism and method for actuating the mold cavity forming dies of such machine.

Such casting technique is commonly referred to as injection molding and, as is well known, the high pressures under which plasticized material is forced into a molding cavity defined between separable dies necessitates application of large forces on the dies to retain them in a closed position during casting, and, of course, the machine as a whole must be of strong and rigid construction to safely and effectively withstand such high pressures and large forces. Also, in most casting machines one of the dies is fixed relative to the machine and the other is movable in a horizontal direction relative to said fixed die, thus presenting several problems for which solutions have been found but often at excessive cost and extra nuisance and difficulty. Some of the problems concomitant with the use of such machines are the retaining of mold inserts in place during casting, the adaptation of the casting ejecting mechanism to the single movable die and the trimming of the sprue or gate from the casting. As to the retaining of inserts in place, it is evident that special clamping fixtures and adaptors must often be resorted to in order to retain the inserts within the vertically disposed die. As to the ejector mechanism, it can be seen that by making both dies movable, the problem is simplified in that such mechanism can be associated with either die depending on convenience rather than necessity. As to the trimming of the sprue or gate from the casting, it can be seen that if it is in the parting line between the dies and enters the mold cavity from an outer surface thereof, it is a simple matter to trim it off from the outer surface of the casting, as compared with trimming it from some inner surface of the casting, as is generally the case where the sprue or gate is at the center of the dies and the mold cavity is disposed concentrically thereabout. In the latter instance, the sprue or gate could be arranged so that the molding material is injected into the mold cavity from the outer periphery thereof but such off-center arrangement is not feasible primarily because the eccentric loading thus imposed on the dies results in excessive flash on the casting, particularly in the portions thereof farthest away from the sprue. Furthermore, such arrangement is usually not feasible because of the increased vertical ex-

2

tent of the dies and the consequent excess weight thereof.

It is one principal object of this invention to provide in a machine having a horizontally movable platen and a fixed platen, a simple mechanism in which the dies are mounted horizontally, in which both dies are movable, and in which the sprue therefor is in the horizontal parting line between the dies and in communication with the mold cavity at the outer periphery thereof to thus avoid all of the aforesaid typical problems.

It is another object of this invention to provide a mechanism by means of which the horizontally disposed dies can be much more firmly clamped than in the original machine having vertically disposed dies. That is to say that the dies can be clamped together with the same or a greater force than those in the original machine but with much less stress on the toggle linkage associated with the movable platen.

It is another object of this invention to provide a die actuating mechanism in which the dies are positively closed by interengaging wedge surfaces on the platens and on the die carrying members.

It is another object of this invention to provide a die actuating mechanism which is capable of simultaneously moving the dies in unison away from the injection nozzle of the machine to sever the molding material at a point between the nozzle and the mold cavity and of separating the dies to permit removal of the completed casting.

It is another object of this invention to provide a die actuating mechanism in which the interengaging wedge surfaces of the platens and the dies are disengaged by means of a novel lost motion connection prior to effecting separation of the dies.

It is another object of this invention to provide novel means for translating relative movement of the platens into relative movement of the dies in a direction transverse to that of said platens.

Additional objects and advantages of the invention will become apparent as the following description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a front elevation view, partly in section,

of a portion of a typical machine of which the die actuating mechanism constituting the present invention is a part, such machine being shown with the dies in a closed position;

Fig. 2 is a view similar to Fig. 1 but with the dies in an open position;

Figs. 3, 4 and 5 are detail views of one form of lost motion connection means between the movable platen of the machine and the die carrying members, Fig. 3 being a view of the left-hand end of Fig. 4, and Fig. 5 being a transverse cross section view taken along line 5-5 of Fig. 4;

Fig. 6 is a longitudinal center vertical cross section view through the die actuating mechanism showing the dies in a closed position, such view being taken along line 6-6 of Fig. 7;

Fig. 7 is a transverse vertical cross section view taken along line 7-7 of Fig. 6;

Fig. 8 is a central horizontal cross section view taken along line 8-8 of Fig. 6;

Figs. 9, 10, and 11 are views of a modified form of lost motion connection between the die carrying members and the movable platen of the machine, Figs. 9 and 10 respectively showing the position of such lost motion connection when the dies are in closed and in opened positions, and Fig. 11 showing such lost motion means in perspective; and Figs. 12 and 13 are views corresponding to the upper left hand portion of Fig. 7 but illustrating a modified form of pivotal connection between the respective ends of the links and the die carrying members and the lug plates.

Referring now to the drawing, the casting machine as a whole is, except for the features herein embodied, of form substantially identical with that of Lester Patent 2,262,615 issued on Nov. 11, 1941, and such machine, although described herein in relation to the present improvements, is to be regarded as merely typical.

As shown in Figs. 1 and 2, the machine comprises a frame 1 of generally box type construction, at one end of which an injection cylinder and nozzle assembly 2 is swingably mounted about a vertical axis and at the other end of which is mounted a hydraulic piston and cylinder, not shown, the horizontal rod 3 of which is adapted to reciprocate longitudinally of the base.

The injection cylinder and nozzle assembly 2 generally comprises an injection cylinder 4, a feed hopper 5 for supplying molding material in granular, chip or finely divided form into the injection cylinder 4, a heated spreader 6 through which the material is forced under pressure by the plunger 7 reciprocable in the injection cylinder 4, and an injection nozzle 8 from which the material in plasticized condition is injected into a mold cavity in communication with the injection nozzle. This assembly is firmly supported vertically with the injection nozzle portion thereof in alignment with the mold cavity sprue opening by means of a suitable adjusting screw 9 threaded into frame 1.

Within frame 1 and in abutting relation to the end thereof which carries the injection cylinder assembly 2 is a fixed platen 10. Movable horizontally and relative to the fixed platen 10 is a movable platen 11 and an auxiliary platen 12, the latter two being adjustable relative to one another by means of a screw 13 which is rotatable but non-movable longitudinally in one of them and in threaded engagement with the other of them. Any well known means may be employed to effect rotation of screw 13, as for example by means of a bevel gear and pinion, not shown, in which the pinion is rotated by a crank

14 or the like. The purpose of screw 13, as will become apparent as this description proceeds, is to enable adjustment of platen 12 so that it is spaced a predetermined distance from platen 10 when the toggle linkage, generally indicated at 15, is in die closing position, as shown in Fig. 1. The toggle linkage is, of course, merely typical and therefore may be of any desired form, the desired action thereof being to effect rapid low power movement of platen 12 to and from a die closing position and to effect a final high power movement of platen 12 to firmly close the dies. It can be seen from Figs. 1 and 2 that reciprocation of rod 3 in opposite directions will effect, through the linkage 15 which is connected to rod 3, the aforesaid low and high power movements of platen 12. The movements of platens 11 and 12 are guided in suitable ways 16 fixed to frame 1. Platens 11 and 12 are further guided in their movements by suitable guide rods 17 disposed on either side of piston rod 3 and secured to platen 11 and slide-guided in suitable bushings (not shown) in the frame.

Having thus generally described a typical casting machine, reference will now be made to the mechanism for effecting vertical separation of the dies and to the various features incorporated in such mechanism.

Attached to fixed platen 10 is an adaptor plate 18 having a sprue bushing 19 fitted into a central horizontal opening therein. Secured to the opposite ends of plate 18 are a pair of lug plates 20 which are spaced from one another and which project toward platen 12. Plates 20 are cut away as shown at 21 to provide free access to the die cavities when the dies are in open position as shown in Fig. 2.

Plate 18 is provided with a recess in its face directed toward platen 12 for receiving the ends of a pair of die carrying members 21 and 22, the recess being preferably provided with hardened wedge strips 23 each having a surface slightly inclined from horizontal and engageable with correspondingly inclined surfaces on the die carrying members 21 and 22. While no particular means is illustrated for adjusting the vertical space between the wedge strips 23, it will be apparent to those skilled in the art that any suitable means may be employed, as for example, the wedge strips 23 may be mounted so as to be movable lengthwise along an inclined plane. That is to say that the upper and lower wedge strip supporting walls of the recess in plate 18 may be inclined slightly from horizontals when viewed from the right hand end of Fig. 6. Hardened wedge strips 24 are also preferably fixed in a recess in a plate 25, which plate is secured to the auxiliary platen 12, such strips 24 facing toward the strips 23 and being engageable with the opposite ends of the die carrying members 21 and 22. Strips 24 may also be made adjustable vertically as described above with reference to strips 23.

In the following description and in the claims the die carrying members 21 and 22 are referred to simply as dies, inasmuch as it does not form any part of this invention to make the actual dies separate of the die carrying members 21 and 22.

Pivotedly secured to each plate 19, as by means of shoulder screws 26 threaded into each plate 19, are two pairs of links 27 and 28, all of which are preferably of the same length. The other end of each link 27 and 28 is pivotally connected to the dies 21 and 22 respectively, as by means of shoulder screws 29 threaded into the dies. The

location of the pivot points on plates 19 and on dies 21 and 22 is preferably such that when the dies 21 and 22 are in abutting relation and in engagement with the wedge strips 23 and 24, as shown in Figs. 1 and 6, the links 27 and 28 will be parallel, vertical and in alignment with one another.

It will now be apparent that if dies 21 and 22 are pulled horizontally toward the left relative to fixed platen 10, as viewed in Figs. 1 and 6, the parallel links 27 and 28 will permit such relative movement and will, at the same time, effect movement of the dies in a vertical direction relative to one another to a separated position as shown in Fig. 2. To further assure that the dies 21 and 22 will only move vertically relative to one another, several vertically disposed dowel pins 30 are secured in one of the dies and projected into bores in the other of said dies, said dowel pins being slideable in such bores during relative movement of the dies. However, it is to be noted that in order to be able to pull dies 21 and 22 toward the left, as described above, there must be a lost motion connection between platen 12 and the dies 21 and 22 to effect relative horizontal movement between them to disengage the wedge surfaces of strips 24 and dies 21 and 22. It can be clearly seen from Fig. 6, for example, that it would be impossible to move platen 12 and dies 21 and 22 in unison with the wedge surfaces engaged as shown. In addition to providing a lost motion connection to permit such relative horizontal movement, the connection must be such that it will permit vertical separation movement of the dies as the horizontal movement of platen 12 continues. We have shown two forms of such connection, viz., that of Figs. 1-8 and that of Figs. 9-11 and such connections will now be described in detail.

In the form of connection shown in Figs. 1-8 and particularly in Figs. 3, 4 and 5, each die is provided with a pair of longitudinal recesses from each of which a lug 31 projects. Slide guided in each such recess is a slide bar 32 which is provided with an elongated slot 33 surrounding lug 31. It is preferred that the right-hand end of the slide bar 32 be short of positively engaging the end wall 34 of the recess in the dies. And likewise, that the left-hand end of slot 33 never engage with the left-hand end of lug 31 so that the final clamping or closing of the dies is effected equally by the wedging of the dies between the wedge strips 23 and 24. It can be seen that because slot 33 is longer than lug 31, the slide bar 32 can partake of movement toward the left, as viewed in Figs. 1 and 4, relative to the dies. Such relative movement effects disengagement of the wedge surfaces of strips 24 from the dies 21 and 22. Such relative movement ceases as soon as the right-hand end wall of slot 33 engages with the right-hand end of lug 31. When such engagement occurs, the dies 21 and 22 will be pulled horizontally toward the left in unison with slide bar 32.

To yieldably retain the right-hand end wall of slot 33 in engagement with the right-hand end of lug 31, the slide bar 32 has a bore therein in which an end of a rod 35 is urged into engagement with the left-hand end of lug 31 by means of a spring 36 which is compressed between the other end of rod 35 and a plug 37, threaded into the outer end of such bore.

Having described the horizontal lost motion connection, reference will now be made to that part of the connection which permits vertical

separation of the dies simultaneously during horizontal movement thereof. The bar 32 is provided with an inturned end 38 which engages in a vertical jib 39 defined by auxiliary platen 12 and plate 25. Thus, it can be seen that as the dies separate, the end 38 of slide bar 32 slides vertically in jib 39.

When the above-described mechanism is in the position shown in Fig. 2 with the dies separated from one another, the right-hand end of lug 31 is held in engagement with the right-hand end wall of slot 33 by means of spring 36 and rod 35. When the platen 12 is moved toward the right through rod 3 and toggle linkage 15, the dies 21 and 22 will move toward the right in unison with platen 12, thus swinging the links 27 and 28 toward an alignment position and causing relative movement of the dies vertically relative to one another. Such vertical movement of the dies is permitted by the sliding connection between slide bar 32 and platen 12. When the links 27 and 28 reach an aligned position, the right-hand ends of the dies are disposed in the recess in plate 17 between the wedge strips 23 and, therefore, further right-hand movement of platen 12 will be relative to the dies and thus will effect compression of spring 36 to bring the wedge strips 24 into engagement with the left-hand ends of the dies. From this point on, the high power right-hand movement of platen 12 effected by linkage 15 and the further multiplication of such high power movement by the wedge surfaces of strips 23 and 24 results in a tremendous vertical clamping force to firmly hold the dies in engagement with one another. As a matter of fact, such clamping force is of magnitude several times that of the force exerted through the toggle linkage 15. Therefore, if the force exertible through toggle linkage 15 is sufficient in the case of vertically disposed dies, as shown in Lester Patent 2,262,615, the mechanism may be so adjusted that such force is what finally clamps the dies in the present instance, in which case the stress on the linkage 15 would be but a small fraction of that which such linkage is subjected to in the machine disclosed in the aforesaid patent.

In finally closing the dies as described above, it is to be understood that the ends of the dies 21 and 22 do not engage the bottoms of the recesses in the plates 17 and 25. Also if the links 27 and 28 are of length such that some clamping of the dies is effected by the toggle action thereof when being swung into alignment, it can be seen that compressive stresses in said links are relieved by the final closing action effected through the wedge strips. It is preferred, however, that the dies just barely or lightly engage one another when the links 27 and 28 are in alignment, whereupon the final closing movement effected by the interengagement of the wedge surfaces takes up the tolerance between the links and their respective pivots 26 and 29. Such tolerance is preferably of the order of .001 of an inch or less and, therefore, by so arranging the dies and links, no stress of any kind is imposed on the links.

As to the movement of platen 12 toward the left from the position of Fig. 1, it can be seen that the forces exerted through springs 36 retain the dies 21 and 22 in engagement with wedge strips 23 and that the platen 12 can move horizontally relative to the dies to effect disengagement of the wedge strips 24 therefrom. When the right-hand end of slot 33 in slide bar 32 engages

with the right-hand end of lug 31, the dies are positively pulled away from plate 17 and strips 23 and thus are moved horizontally in unison and at the same time are vertically separated from one another.

Inasmuch as the only difference between the mechanism of Figs. 9-11 and that of Figs. 1-8 is in the lost motion connection between the auxiliary platen 12 and the dies 21 and 22, the following description is restricted to such difference without repeating the general operation of the platen 12, the toggle linkage 15, the action of the wedge strips 23 and 24, etc.

As clearly shown in Figs. 9-11, plate 25 and each die is provided with brackets 40 and 41. Links 42 and 43, pivotally connected to one another and to the brackets 40 and 41, operate as the lost motion connection to permit relative horizontal movement of platen 12 and dies 21 and 22 and relative vertical movement of the dies and the platen 12. Link 43 is provided with oppositely extending arms 44 and 45, the former being engageable with die 21 or 22, as the case may be, and the latter being engaged by one end of a spring 46 which is compressed between die 21 or 22 and arm 45.

When the parts are in the position illustrated in Fig. 9, a force exerted toward the right by platen 12 effects tight closing of the dies 21 and 22, the above-described lost motion connection permitting relative movement between platen 12 and platen 10, or between platen 12 and the dies 21 and 22. Now, if the platen 12 is moved toward the left, the effect of springs 46 is to hold the dies 21 and 22 in engagement with wedge strips 23 associated with plate 17. Such relative movement continues until arm 44 of link 43 engages its respective die. At this time, the wedge strips 24 associated with plate 25 are out of engagement with the left-hand ends of the dies 21 and 22. The platen 12 then exerts a positive pull on the dies 21 and 22 to pull them toward the left and thus effect the swinging of the links 27 and 28 to effect vertical separation of the dies as shown in Fig. 10. During separation of the dies, the links 42 swing to the position shown in Fig. 10.

During opposite movement of platen 12, that is toward the right, the springs 46 serve to retain arms 44 in engagement with the dies 21 and 22 until the right-hand ends of the dies are disposed within the recess in plate 17 and in engagement with the wedge strips 23 therein. Thereafter lost motion movement occurs to compress the springs 46 and thereby effect the final clamping of the dies between the wedge strips 23 and 24.

To further exemplify the advantage of the present invention, we have illustrated in Figs. 6, 7 and 8 a typical die D comprising two sections, one of which is bolted to die-carrying member 21 and the other of which is bolted to die-carrying member 22. The dies herein illustrated include in their parting line the usual gates and runners 47 between the mold cavities 48 and the opening in the sprue bushing 18, inserts 49 extending into the cavities 48, and suitable insert holders 50. The primary function of the holders 50 is to shorten the operating cycle of the machine by permitting loading of the several inserts 49 thereinto while the plastic material is being injected into and is setting in the cavities 48 in the batch previously placed in the machine. In other words, when the dies are separated as in Fig. 2, the holder and its several inserts can quickly be placed in the dies thus saving the time of placing the inserts one by one in the cavities 48.

As shown in the drawing, the dies D are also short of engaging the plates 17 and 25 as are the die-carrying members 21 and 22. In order to prevent leakage of plasticized material between the right-hand end of the dies and the left-hand end of the sprue bushing 18 during injection, these abutting surfaces are polished and lapped together to form a tight seal and are arranged to resiliently engage one another when the dies are in the finally closed position of Fig. 1. One manner of accomplishing such resilient engagement is to make the sprue bushing 18 of such length that it normally projects beyond the plate 17 a distance exceeding the clearance between plate 17 and the right-hand end of dies D whereby when the dies are moved to a finally closed position, the sprue bushing 18, the discharge nozzle 8 and the injection cylinder assembly 2 will be forced toward the right as viewed in Fig. 1, the strap 51 which straddles the opening at that end of the base 1 being capable of yieldably bending in its mid section to permit such movement. The amount of such movement is, of course, very slight, preferably about .005 of an inch to assure firm yieldable engagement of the dies with the sprue bushing 18, but without danger of overstressing any of the parts.

From the above description relative to dies D, it can be seen that even for the simple inserts shown there would be considerable difficulty in holding the inserts in place between dies which are vertically disposed and movable horizontally relative to one another.

Another feature previously mentioned was that in making both die sections movable the ejector mechanism could be associated with either one or both depending on convenience rather than on necessity. In Figs. 6 and 7 we have shown one simple form of ejector mechanism which comprises ejector pins 52 carried by an ejector plate 53, the pins being here engageable with one of the holders 50 to lift the same vertically upward relative to the lower die section when the dies are separated. The ejector plate 53 is slide guided vertically relative to die-carrying member 22 by rods 54 fixed therein. The relative vertical movement of the ejector mechanism relative to the lower die section is effected by interrupting movement of the ejector plate 53 during separation of the dies by means of an adjustable stop 55 carried by a bracket 56 attached to plate 25. While in most instances the molded article will remain or stick in the lower die section, there may be instances where it is desirable or necessary to provide an ejector mechanism in the upper die section, in which case the same can be very readily and conveniently accomplished in much the same manner as that just described. To those skilled in the art, it will be apparent that springs, push pins and the like may be employed with the ejector mechanism to assure that when the dies are in closed position the ends of the ejector pins, where they operate directly on the molded article, will be flush with the contour of the article. In the particular mechanism shown, the position of the ends of the ejector pins 52 is not critical just so long as the pins move downwardly far enough to permit full closing of the dies.

One advantage of the die actuating mechanisms herein disclosed which has not been especially emphasized in the preceding description is that the horizontal movement of the dies relative to the heated injection nozzle 8 while the casting is gripped between the dies assures that the sprue

will always break away from the nozzle at the end of the nozzle where the material is soft and of smallest cross-section. As is well known to those skilled in the art, in conventional mechanisms breaking of the sprue from the gate or runners of the casting and the sticking thereof in the sprue bushing is an ever present problem causing considerable trouble and loss of time. Such undesirable breaking usually occurs when the juncture of the sprue and runners is soft as the die opens, or when the sprue cools and sticks in the sprue bushing. Of course, one manner of alleviating such problem has been to employ so-called "sucker" pins but such can only be provided at added expense. In the present case such problem is simply and effectively remedied without employment of "sucker" pins or the like.

As briefly indicated previously, the fact that both die sections are movable makes it possible to employ the ejector mechanism with either die section. In this way the ejector pins can conveniently be arranged to bear against unseen portions of the casting. In the conventional machines wherein only one die section is movable and the ejector mechanism is associated therewith and wherein the deepest portion of the casting is in such movable die for the purpose of increasing the adhesion between the casting and the die to assure that the casting will be retained in that die section which has the ejector mechanism, the ejector pins must, of necessity, be often brought to bear on surfaces of the casting which should preferably be smooth and free of all marks. In order to avoid such undesirable mar-ring of the casting, die designers have often been called upon to design less efficient and harder to make dies, or else to redesign the article to be cast. Either case entails considerable expense, all of which can be avoided by making both dies movable so that the ejector mechanism, the deepest cavity, etc. can be embodied at will in either die.

An improved form of pivotal connection between the ends of links 27, 28 and die carrying members 21, 22 and lug plates 19 is illustrated in Figs. 12 and 13. This connection, as shown, comprises a bushing 58, the opposite ends of which are respectively press fit and slip fit into openings in lug plate 19 and link 27. That end of bushing 58 which is press fitted into lug plate 19 is internally threaded for a portion of its length and the other end is counterbored as at 59. A bolt 60 in threaded engagement with threads formed in plate 19 and having a head portion within the counterbore 59 assures that the bushing will be retained against axial movement and rotation. The radially extending flange portion 61 of the bushing, in turn, retains the link against axial displacement relative to the bushing 58. Thus, it can be seen that the link 27 can freely partake of pivotal movement about bushing 58 without tending to loosen the same. In other words, the press fitting of the bushing in plate 19 resists rotation of the bushing as does bolt 59. It is to be understood that the other end of link 27 is pivotally connected in the same manner with the bushing press fitted into one of the die carrying members.

If it be desired to disassemble the die mechanism or to replace bushing 58, any bolt 62 having the same size threads as those in the bushing may be used. To remove bushing 58, bolt 60 is first removed and then such bolt 62 is merely screwed into the bushing. The engagement of the end of the bolt with the bottom wall 63 of the bore

in plate 19 urges bushing 58 toward the right out of engagement with the bore in plate 19. In Fig. 13 the bushing 58 is shown partially removed.

Other modes of applying the principle of the invention may be employed, change being made as regards the details described, provided the features stated in any of the following claims or the equivalent of such be employed.

We therefore particularly point out and distinctly claim as our invention:

1. In a casting machine or the like, the combination of a pair of dies adapted to be relatively moved toward and away from one another, a pair of die actuating members relatively movable in opposite directions and transverse to such relative movement of said dies, means connecting said dies and members for moving said dies toward one another into closed position in response to relative movement of said members in one direction, and interengageable wedge means on said dies and said members for effecting final closing of said dies upon continued relative movement of said members.

2. In a casting machine, the combination of a pair of dies adapted to be relatively moved toward and away from one another, a pair of members movable relative to one another in a direction transverse to such relative movement of said dies, and link means interconnecting said dies and members for moving said dies in opposite directions toward one another into closed position and away from one another into open position in response to relative movement of said members in opposite directions, said members and dies being formed with interengageable surfaces operative to effect final closing of the latter upon continued relative movement of said members in the die-closing direction.

3. In a casting machine or the like, the combination of a pair of dies adapted to be relatively moved toward and away from one another, and a pair of members movable relative to one another in a direction transverse to such relative movement of said dies, both of said members being connected to at least one of said dies, the connection between one of said members and said one die comprising a link pivotally connected to each, said link being disposed at an angle relative to such transverse movement of said members at least when said dies are in closed position.

4. In a casting machine or the like, the combination of a pair of dies adapted to be relatively moved toward and away from one another, a pair of members movable relative to one another in a direction transverse to such relative movement of said dies, both of said members being connected to at least one of said dies, the connection between one of said members and said one die comprising a link pivotally connected to each, said link being disposed at an angle relative to such transverse movement of said members at least when said dies are in closed position, and the connection between the other of said members and said one die comprising slidably engaged portions permitting a predetermined amount of relative movement of said members independent of relative movement of said dies.

5. In a casting machine or the like, the combination of a pair of dies adapted to be relatively moved toward and away from one another, a pair of members movable relative to one another in a direction transverse to such relative movement of

said dies, and parallel links out of line with such transverse movement at least when said dies are closed, pivotally connected to each of said dies and to one of said members, the other of said members being connected to each of said dies so that relative movement of said members away from one another effects swinging of said links toward alignment with such transverse movement and thus relative movement of said dies away from one another.

6. In a casting machine or the like, the combination of a pair of dies one above the other and movable relatively toward and away from one another, members movable horizontally relative to one another into and out of engagement with said dies, said dies and said members including wedge surfaces effective when engaged to urge said dies into engagement with one another, means vertically movably connecting both of said dies to one of said members, and link means connecting both of said dies to the other of said members, said link means being disposed at an angle relative to the path of movement of said members at least when said dies are together whereby relative movement of said members away from one another effects separation of said dies.

7. In a casting machine or the like, the combination of a pair of dies adapted to be relatively moved toward and away from one another, a pair of die actuating members movable in a direction transverse to such relative movement of said dies into and out of engagement with said dies, said dies and said members including wedge surfaces effective when engaged to urge said dies into engagement with one another, link means connecting one of said members to said dies, and lost motion connecting means between the other of said members and said dies for effecting disengagement of such wedge surfaces upon relative movement of said members away from one another, said link means being disposed angularly relative to the path of relative movement of said members at least when the aforesaid wedge surfaces are disengaged whereby continued movement of said members effects separation of said dies.

8. In a casting machine or the like, the combination of a pair of dies adapted to be relatively moved toward and away from one another, relatively movable members movable in a direction transverse to such relative movement of said dies, means for translating movement of said members into movement of said dies, said means including a lost motion connection between said members and said dies for permitting limited relative movement of said members prior to effecting relative movement of said dies, said lost motion connection comprising a lug on each of said dies, a slide member fitted over said lug and slidably transversely on each of said dies and connected to one of said members, said slide member being formed with an elongated slot therein one end of which is engageable with said lug to effect relative movement of said dies in response to further relative movement of said members.

9. In a casting machine or the like, the combination of a pair of dies adapted to be relatively moved toward and away from one another, relatively movable members movable in a direction transverse to such relative movement of said dies, means for translating movement of said members into movement of said dies, said means including a lost motion connection between said members and said dies for permitting limited relative movement of said members prior to effecting relative movement of said dies, said lost motion connection comprising a lug on each of said dies, a slide member fitted over said lug and slidably transversely on each of said dies and connected to one of said members, said slide member being formed with an elongated slot therein one end of which is engageable with said lug to effect relative movement of said dies in response to further relative movement of said members.

tive movement of said dies, said lost motion connection comprising a lug on each of said dies, a slide member fitted over said lug and slidably transversely on each of said dies and connected to one of said members, said slide members being formed with an elongated slot therein one end of which is engageable with said lug to effect relative movement of said dies in response to further relative movement of said members, and a spring urging said slide member toward a position with such end in engagement with said lug.

10. In a casting machine or the like, the combination of a pair of dies adapted to be relatively moved toward and away from one another, relatively movable members movable in a direction transverse to such relative movement of said dies, means for translating movement of said members into movement of said dies, said means including a lost motion connection between said members and said dies for permitting limited relative movement of said members prior to effecting relative movement of said dies, said lost motion connection comprising a link pivotally connected to each die and to one of said members, said link including an arm engageable with said die to effect relative movement of said dies in response to further relative movement of said members.

11. In a casting machine or the like, the combination of a pair of dies adapted to be relatively moved toward and away from one another, relatively movable members movable in a direction transverse to such relative movement of said dies, means for translating movement of said members into movement of said dies, said means including a lost motion connection between said members and said dies for permitting limited relative movement of said members prior to effecting relative movement of said dies, said lost motion connection comprising a link pivotally connected to each die and to one of said members, said link including an arm engageable with said die to effect relative movement of said dies in response to further relative movement of said members, and a spring compressed between said die and said link urging said arm into engagement with said die.

12. In a casting machine or the like, the combination of a fixed member formed with an opening therethrough, a horizontally disposed injection nozzle in such opening, vertically separable and horizontally movable dies formed with a molding cavity and defining when closed a sprue in their parting line in register with said nozzle, a horizontally movable member spaced from said fixed member and movable toward said fixed member to clamp said dies, said members and said dies including wedge surfaces to translate such horizontal clamping force into a vertical die closing force, means connecting said dies with said movable member, and link means connecting said dies with said fixed member and so arranged as to be responsive to movement of said movable member away from said fixed member to separate said dies.

13. In a casting machine, the combination of a pair of vertically disposed and relatively horizontally movable die clamping members, a pair of side plates on one of said members extending toward the other of said members, a pair of dies between said members having a horizontal parting line, parallel link mechanisms connecting said dies to said plates for swinging movement of the former toward and away from one another, and means connecting said other of said members to said dies whereupon relative horizontal move-

met of said members in opposite directions effects swinging of said dies as aforesaid, the opposed vertical faces of said members and the opposite ends of said dies being formed with interengageable wedge surfaces operative when said members are moved toward one another into engagement with the dies therebetween to clamp the latter together.

14. In a casting machine, the combination of a pair of vertically disposed and relatively horizontally movable die clamping members, a pair of side plates on one of said members extending toward the other of said members, a pair of dies between said members having a horizontal parting line, parallel link mechanisms connecting said dies to said plates for swinging movement of the former toward and away from one another, and means connecting said other of said members to said dies whereupon relative horizontal movement of said members in opposite directions effects swinging of said dies as aforesaid, the opposed vertical faces of said members and the opposite ends of said dies being formed with interengageable wedge surfaces operative when said members are moved toward one another into engagement with the dies therebetween to clamp the latter together, said last-named means comprising bars vertically slidably connected to said other of said members and connected to said dies.

15. In a casting machine, the combination of a pair of vertically disposed and relatively horizontally movable die clamping members, a pair of side plates on one of said members extending toward the other of said members, a pair of dies between said members having a horizontal parting line, parallel link mechanisms connecting said dies to said plates for swinging movement of the former toward and away from one another, and means connecting said other of 40

said members to said dies whereupon relative horizontal movement of said members in opposite directions effects swinging of said dies as aforesaid, the opposed vertical faces of said members and the opposite ends of said dies being formed with interengageable wedge surfaces operative when said members are moved toward one another into engagement with the dies therebetween to clamp the latter together, said last-named means comprising bars vertically slidably connected to said other of said members and connected to said dies, the connection of said bars with said dies including a horizontal lost-motion connection so formed that such wedge surfaces on said members and dies are disengaged in response to relative movement of said members away from one another and prior to swinging of the dies away from one another upon continued movement of said members away from one another.
